Primary Examiner — Andrew Kerr(57) **CLAIM**

The ornamental design for a modular beverage container, as shown and described.

DESCRIPTION

FIG. 1 is a top-front-left perspective view of a modular beverage container showing my new design in a disassembled configuration;

FIG. 2 is a bottom-front-left perspective view thereof;

FIG. 3 is a top-rear-right perspective view thereof;

FIG. 4 is a bottom-rear-right perspective view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a right elevational view thereof;

FIG. 10 is a left elevational view thereof;

FIG. 11 is a top front perspective view of the modular beverage container in an assembled configuration; and,

FIG. 12 is a bottom rear perspective view thereof.

The broken lines in the drawings depict portions of the modular beverage container that form no part of the claimed design.

1 Claim, 12 Drawing Sheets(56)
